US0D1027699S

(12) **United States Design Patent** (10) Patent No.: **US D1,027,699 S**
(45) Date of Patent: ** May 21, 2024

(54) **WATCH BAND**

(71) Applicant: **Shenzhen Qipurui Technology Co., Ltd.**, Shenzhen (CN)

(72) Inventor: **Qiaoyuan Huang**, Shenzhen (CN)

(73) Assignee: **Shenzhen Qipurui Technology Co., Ltd.**, Shenzhen (CN)

(**) Term: **15 Years**

(21) Appl. No.: **29/919,230**

(22) Filed: **Dec. 1, 2023**

(30) **Foreign Application Priority Data**

Nov. 27, 2023 (EM) 015042400-0004

(51) **LOC (14) Cl.** **11-01**

(52) **U.S. Cl.**

USPC **D11/3**

(58) **Field of Classification Search**

USPC D11/1-16, 93; D10/30, 31, 32, 38, 70; D14/344
